UNITED STATES PATENT OFFICE

2,048,353

AUTOMATIC COCK LOCK

Joseph F. Rose, Battle Creek, Mich.

Application December 18, 1935, Serial No. 55,111

1 Claim. (Cl. 303—86)

This invention appertains to new and useful improvements in locking means for the valves of railroad train air line cocks.

The principal object of the present invention is to provide a lock which will be automatic in operation, locking the valve either in open or closed position.

Other important objects and advantages of the invention will become apparent to the reader of the following specification.

In the drawings:

Figure 1 represents a side elevation.

Figure 2 is a top plan view.

Figure 3 is a fragmentary longitudinal sectional view.

Figure 4 is a cross sectional view on line 4—4 of Figure 3.

Figure 5 represents a fragmentary detailed sectional view of the cam means for the lock.

Figure 6 represents a side elevational view of the cam.

Figure 7 represents a perspective view of the piston and rod.

Referring to the drawings wherein like numerals designate like parts, it can be seen that numeral 5 represents the barrel of the cock with numeral 6 the laterally disposed connecting head therefor. Numeral 7 represents the usual cock plug of the rotary type which extends upwardly and is provided with the squared reduced portion 8 at the top thereof. Connection is made at one end of the barrel 5 to the usual hose or pipe line 9 of the train system.

The reduced and squared portion 8 extends into the cam head 10 and this cam is provided with a grooveway 11 merging at one end with a recess 12 and at its other end with a recess 13. This cam head 10 is provided with a laterally disposed handle 14.

The upper portion of the barrel 5 is bored to provide the cylinder 15 in which the piston 16 is movable.

The plug 17 is threaded into one end of this cylinder 15 and is provided with a bore 18 there-

in for receiving one end of the piston rod 19. The other end of the piston rod extends through the other end of the cylinder 15 and is engageable in the groove 11 or either one of the recesses 12 or 13 depending upon which extreme position the valve 7 is to be retained in.

A coiled compressible spring 20 is interposed between the end walls 21 and the piston 16 for normally maintaining the piston 16 urged toward the right in Figure 3.

A by-pass opening 22 communicates the barrel 5 with the cylinder 15 so that air behind the piston 16 will urge the rod 19 against the cam 10 and when the rod is engaged into one of the recesses 13 or 12 the cam cannot be rotated.

While the foregoing specification sets forth the invention in specific terms, it is to be understood that numerous changes in the shape, size and materials may be resorted to without departing from the spirit or scope of the invention as claimed hereinafter.

Having thus described the invention, what is claimed as new is:

In a railroad train line air cock, comprising a barrel having a rotary cock therein, a cam mounted on the cock, a cylinder on the barrel closed at one end and open at its opposite end, an elongated guide member, a plug head on one end of the guide member for disposition into the open end of the cylinder and having an axial bore therein, a piston slideable in the cylinder, spring means in the cylinder for urging the piston normally in a direction toward the plug, and a rod on the piston extending at one end through the closed end of the cylinder and having its opposite end riding in the axial bore of the plug and in the guide, said cam being provided with an opening on the periphery thereof into which the said rod can engage at one end, said barrel being provided with an opening communicating the interior thereof with the interior of the cylinder at a point between the plug and the piston.

JOSEPH F. ROSE.
